HARDBOARD PANELING OR THE LIKE

Daniel R. Nikolich, Palatine, Ill., assignor to Edward Hines Lumber Co., a corporation of Delaware

Filed Jan. 8, 1962, Ser. No. 68,213

Term of patent 14 years

(Cl. D13—1)

FIG. 2

The rear of the paneling has substantially the same appearance as the front shown on the drawing.

I claim:

The ornamental design for a hardboard paneling or the like, as shown and described.
